UNITED STATES PATENT OFFICE.

LAWRENCE L. McCULLOUGH, OF KANSAS CITY, KANSAS.

BALLAST-BURNING MACHINE.

1,135,307.

Specification of Letters Patent. Patented Apr. 13, 1915.

Application filed January 20, 1913. Serial No. 743,055.

To all whom it may concern:

Be it known that I, LAWRENCE L. McCULLOUGH, a citizen of the United States, residing at Kansas City, in the county of 5 Wyandotte and State of Kansas, have invented certain new and useful Improvements in Ballast-Burning Machines, of which the following is a specification.

In burning ballast for railways or other 10 similar purposes, it is customary to have an open kiln or pit in which the ballast is burned by depositing successive layers of coal and clay upon a sloping bank. The 15 heat from the burning coal burns or vitrifies the clay until it is of proper consistency for ballast. It is more or less customary to form a "top" along the upper portion of the face of the fire. After a fire has been well started the upper surface of the completed ballast 20 will lie comparatively flat and the "top" just mentioned constitutes a slight upward extension of the face of the fire above this flat surface.

The present invention relates to a machine 25 or apparatus for breaking or stirring up the face of the fire, in order to assist the burning action and for pulling over the top onto the face.

Among the objects of the present invention are; to provide a machine or devices 30 for this purpose which may be readily utilized for breaking up or working the face of the fire and also for pulling top, such operations being done without the necessity 35 of reversing or changing the raking or dragging and top pulling device; to improve the general construction of such apparatus, and to provide such novel features and improvements as will be more fully described and claimed hereinafter.

In the accompanying drawings illustrating my invention, Figure 1 is a diagrammatical view of a machine illustrating its method of operation; Fig. 2 is a front view 45 of the rake or dragging device; Fig. 3 is a side view of the same; Fig. 4 is a plan view; and, Fig. 5 is a side view with parts broken away to show the interior construction.

As shown in these drawings, 6 indicates a 50 car, such as is commonly used for ballast burning purposes, having an outwardly extending boom 7 and a mast 8. The car is preferably counter-balanced in any well known way to support the boom and connected parts. The implement or device 9 for working the fire and pulling the top

comprises a plate or pan, having a bottom 10 and sides 11. The bottom is provided at both ends with strong teeth or plows, the ones at the front end of the implement (the 60 end toward the car) are indicated by the numeral 12, and the ones at the back end, by the numeral 13. The back of the implement is provided with a door 14 which is pivoted at 15' to the sides 11 adjacent to 65 the top of the pan. This door is free to swing inwardly, but is prevented from swinging out by any suitable stop, such as the angle iron 15, which extends across the pan and against which the lower end of the 70 door will strike. A bail 16 is pivoted at 17 to the sides 11 and is provided with a sheave 18. The swinging of the bucket or pan with respect to the bail is limited by forward stops 19 and rear stops 20 on the sides 11. 75 A chain or cable 21 is attached to the sides 11, and is also attached to a drag line 23, which line leads to a winding drum 24 on the car 6. This line is preferably guided by means of a guide roller 25 in the particular 80 arrangement shown in order to give as much of a downward pull on the line 23 as possible. The chain 21 is in the form of a loop and the two side portions thereof are connected by means of chains or cables 26, to 85 the upper horizontal portion of the bail 16. A second cable 27 is connected at the back of the pan or shovel as indicated at 28, and passes up over a sheave 29 at the outer end of the boom 7, thence down and under the 90 sheave 18, then up and over guide sheaves 30 and 31 on the mast 8, and then down to a second winding drum 32 on the car 6. The winding drums 24 and 32 are preferably the regular winding drums of any ordinary or 95 preferred form of hoisting engine. When the apparatus is used for pulling over the top which is indicated at 33 in Fig. 1, the operator slacks off on the line 23 and draws in on the line 27 until the bucket-drag 100 reaches the position shown in full lines in Fig. 1. He then slacks off on the line 27 and draws in on the line 23 which pulls the bucket-drag forward or toward the car. This causes the bucket-drag to gather or 105 loosen a certain amount of the top and pull it over onto the face of the fire. During this movement the bucket may become filled and the material is held therein by the swinging door 14. As soon as the bucket 110 arrives over the face of the fire it may be fully dumped by pulling in on the cable 27,

which causes the rear end of the bucket to be raised. The bucket is again swung over to digging position, and the operation repeated as often as necessary to pull the top, 5 the car being moved along the track as fast as necessary to bring the bucket-drag into successive positions longitudinally of the fire.

There are several operations connected 10 with the proper working of the face of the fire, all of which may be done by means of this apparatus. For instance if it is desired to scoop mud or unburned material out at the bottom of the face, as at a point 15 indicated at 34, the cable 27 is slackened and the drag line 23 pulled in until the bucket-drag arrives at a point slightly above the foot of the fire, at which time the bucket swings over until the stop 20 strikes against 20 the bail and the bucket is approximately in vertical position, then by letting it down until the teeth or plows engage with the material, the material may be scooped out by drawing in on the cable 23.

25 If it is desired to break up the face of the fire, then with the bucket still in substantially vertical position, the cables may be so manipulated as to raise it above the fire and let it drop down until the teeth 12 30 strike into the face. Then, if desired, the face can be further loosened at such point by drawing in on the cable 23.

The face of the fire may be plowed or raked by slackening off on the cable 23 and 35 drawing in on the cable 27, which will draw the bucket-drag up the face of the fire as indicated in dotted lines in Fig. 1. The teeth will then engage with the material and loosen or drag the same, and any material passing over the teeth will go directly through the bucket as the door 14 40 will swing inwardly to allow it to pass and

the material will then slide out at the other end.

It will thus be seen that by means of my 45 improved implement, which for convenience, I have designated as a "bucket-drag," and novel method of operation, a ballast fire can be readily and effectively worked without the necessity of changing or reversing the 50 operating implement, as is now commonly done with drags used in connection with ballast burning.

Having thus described my invention, which however, I do not wish to limit to 55 the particular arrangement shown and described, except as specified in the appended claims, what I claim and desire to secure by Letters Patent is:

1. An implement for working ballast fires 60 comprising an open ended bucket, a swinging door for one end of said bucket, means for preventing the door from swinging outwardly, teeth at either end of said bucket, a bail pivoted to said bucket and means 65 for limiting the swinging movement of the bail with respect to the bucket.

2. In an apparatus for burning ballast fires, the combination of a pan comprising bottom and side members, a door pivoted to 70 the tops of the sides adjacent to one end, a stop for preventing the door from swinging outwardly, plows at either end of said pan, a bail pivoted to the sides, stops for limiting the swinging movement of the bail, a chain 75 or pulling member fastened to the front end of said pan, and connections between said chain and the upper portion of the bail.

LAWRENCE L. McCULLOUGH.
